DIE FOR FORMING GLOVE BLANKS

Louis P. Van der Essen, Gloversville, and James
E. Lesser, Johnstown, N. Y.

Application November 1, 1937, Serial No. 172,092

2 Claims. (Cl. 164—29)

Our invention relates to an improved method in the art of making gloves and to an improved device or improved devices for improving the manufacture of gloves.

One of the objects of the invention is to provide a trunk or blank having suitable openings or perforations through which the needle can be passed, in the operation of sewing the glove, so that it is unnecessary to force the needle through the material of the glove during the sewing operation.

Another object of the invention is to provide improved die means, whereby said perforations are formed simultaneously with the cutting out of the trunk, and said perforations are in proper position and alignment relative to the edge of the trunk, in order to receive the sewing thread.

Whenever we refer to a glove trunk or blank, it is to be understood that we include the various parts of a glove, which are cut separately, and then sewed to each other. The invention can be used in connection with one or more such parts.

Other objects are to provide means for making the improved blank, which means can be made at low cost and which shall be simple to operate.

Other objects of our invention will be set forth in the following description and drawings which illustrate a preferred embodiment thereof, it being understood that the above statement of the objects of our invention is intended generally to explain the same without limiting it in any manner.

Fig. 1 is a top plan view of a die which can be used for making a glove trunk, said die having the improved means for forming the sewing perforations in the material of the trunk.

Fig. 2 is a sectional view on the line 2—2 of Fig. 1.

Fig. 3 is a side elevation of Fig. 1, taken at the right-hand side thereof.

Figs. 4—9 are respectively sectional views on the lines 4—4, 5—5, 6—6, 7—7, 8—8, and 9—9 of Fig. 1.

Fig. 10 is a view similar to Fig. 1 showing the die for cutting out and perforating the thumb portion of the glove.

Fig. 11 is an elevation, partially in section, taken on the line 11—11 of Fig. 10.

Fig. 12 is a sectional view on the line 12—12 of Fig. 10.

Fig. 13 is a top plan view of a combined cutting die and perforating means for forming the side portions of the finger portions of the glove.

Fig. 14 is an elevation, partially in section, on the line 14—14 of Fig. 13.

Fig. 15 is a sectional view on the line 15—15 of Fig. 13.

Fig. 16 is a plan view of the main body of the blank.

Fig. 17 is a plan view of the blank which is used for making the thumb of the glove.

Fig. 18 is a plan view of the blank which is used for making the intermediate or side portions of the fingers of the glove.

Fig. 19 is a plan view of the completed glove.

Fig. 20 is a detail perspective view showing the finger inserts.

Fig. 21 is a partial detail sectional view, showing the assembly of the blanks illustrated in Fig. 16 and Fig. 17.

Heretofore in manufacturing a glove of leather or the like, it has been common practice for many years to cut the various portions of the glove from sheets of leather, by means of cutting dies. These portions of the glove were then sewed by hand. In using the needle, it was necessary to force the same through the material of the glove and this was tedious and difficult work, especially if the glove was made of heavy leather.

While the invention applies to gloves made of all materials, it is particularly useful in connection with the manufacture of gloves made of leather or other material which is difficult to perforate. Likewise work done according to the former method was time-consuming, because it was necessary to make the stitches of uniform length and such work was often irregular and unevenly spaced.

According to the improved method and mechanism, the cutting dies are provided with piercing members which form the thread holes, simultaneously with the cutting of the blank, so that prior to the sewing, the blank is provided with preformed holes for receiving the sewing thread, said holes being evenly spaced and being arranged in suitable parallel relation to the edge or edges of the blank.

Fig. 1 shows a die 1, for cutting and perforating the main portion of the glove. This die has a base 2.

The front edge of the base 2 is provided with an adjustable support 3, which is of angular cross-section, and which is used for supporting one of the cutting knives and two series of perforating members.

As shown in Fig. 1 and Fig. 8, said supporting member 3 is provided with lugs 3a having longitudinal slots 3' and 4'. Clamping screws 5 adjustably connect the lugs 3a to the base 2, so that the member 3 can be adjusted to and fro along a longitudinal line, and said member 3 can then be clamped in adjusted position.

The member 3 has a knife 4 detachably connected thereto by any suitable means, such as fastening members 6. An angular support 7 is connected to the member 3, by means of fastening members 8. The members 3 and 7 have smooth and snugly abutting adjacent faces.

Perforating members P are held in the member 7.

In this particular embodiment two parallel rows of members P are supported in member 7, as shown in Fig. 1.

In finishing the rear edge of the blank, said rear edge is turned inwardly until the holes which have been formed by the two series of members P are superposed in aligned pairs, and 10 the sewing thread T is then passed through said aligned pairs of holes, as shown at the bottom of Fig. 19.

The piercing members P have pointed portions of the usual type, and they also have shanks 15 which may be cylindrical or slightly tapered. A slightly tapered shape is preferred.

The tapered shanks of the piercing members P are located removably in bores of corresponding shape which are provided in the member 7. 20 Hence members P cannot move outwardly relative to member 7, but members P can be moved inwardly relative to member 7, and be separated therefrom, when member 7 is separated from member 3. Hence, if a piercing member P becomes blunt or broken, the member 7 can be detached from the member 3, and the defective piercing member P can be readily removed and replaced.

The inner ends of the piercing members P rest 30 upon the adjacent surface of the member 3. Hence it is unnecessary to provide solder or any permanent connection between the piercing members and member 7, although such permanent connection could be used if desired.

In the particular embodiment illustrated, a longitudinal slit is formed in the body of the glove, at the line 9 which is indicated in Fig. 16.

It is to be understood that many different types of gloves can be manufactured by suitably varying the cutting knives or cutting members, and that the invention is not to be limited to the particular type of glove which is illustrated herein.

The slit along the line 9 is formed by the knife 10, which is shown in Fig. 1 and in Fig. 9. Perforations are also formed adjacent the slit 9, according to the design indicated in Fig. 16, by means of piercing members P' which are arranged according to a corresponding design; as shown in Fig. 1.

The knife 10 is connected removably or in any other suitable manner, to the support 11. The piercing members P' are of the same general construction as the piercing members P. Said piercing members P' are located in bores of a supporting member 12.

The member 12 is connected to the member 11, by means of screws or other fastening members 15.

The butt ends of the piercing members P' are therefore supported upon the adjacent surface of the member 11.

Clamping screws or bolts 14 have their shanks passing through slots 16 of the member 11. The threaded ends of the members 14 are connected 65 to the correspondingly threaded walls of bores or recesses which are formed in the base 2.

Therefore the assembled members 11, 12 and P' can be adjusted longitudinally.

As shown in Fig. 1, the knife 10 projects beyond 70 the rear edge of the top wall of the member 7, so that the rear end of the knife 10 abuts the transverse knife 4. The members 3 and 11 are longitudinally adjusted simultaneously, so as to preserve said relative positions of the knives 4 and 10.

Therefore, the longitudinal slit which is formed by the knife 10, will extend to the rear edge of the glove blank at all times.

The side edges of the principal glove blank, and the finger portions of said principal blank, 5 are cut by means of knives 17, 18, 19, 20, 21, 22, 23 and 24. These knives are made of the shape shown in Figs. 1 and 2 and portions of the adjacent edges of the knife members 17 and 19 closely abut each other, as indicated in Fig. 1. 10

This is also clearly shown in Fig. 4.

Knives 18 and 24 also have abutting edge portions. These abutting edge portions act like single knife edges.

Base 2 has integral upstanding flanges 2a and 15 2b.

As shown in Figs. 4 and 5, knife 17 is connected to flange 2a by screws 26.

Knife 18 is connected to flange 2b by screws 27.

Angular supports 28 and 28a are detachably 20 connected to flanges 2a and 2b, by screws 29.

Said supports 28 and 28a abut the rear walls of blocks 17' and 18'.

Piercing members 17c and 18c are respectively mounted in supports 28 and 28a, which are connected to flanges 2a and 2b by screws 29. 25

Piercing members 17a and 18a are mounted respectively in the blocks 17' and 18'.

These blocks 17' and 18' are connected to flanges 2a and 2b by screws 25. 30

The knives 17 and 18 are respectively connected to the blocks 17' and 18' by screws 26 and 27.

Knives 19, 20, 21, 22, 23, and 24 are clamped between the blocks B and between the corresponding blocks 18', 20', 21', 22', 23', and 24'. Said 35 knives can be secured detachably to said blocks 19'—24'.

Blocks B are connected to base 2 by bolts 26a, whose heads are located in countersunk recesses which are provided in the top surfaces of blocks B. 40

Piercing members 19a, 20a, 21a, 22a, 23a, 24a are respectively mounted in blocks 19'—24', which are detachably connected to blocks B, by screws 25.

The type of glove which is disclosed herein, is 45 provided with triangular inserts 50, at the bases of the finger portions of the glove. These inserts 50 are made from the triangular blanks 51, which are shown in Fig. 16.

Three of such triangular inserts are provided. 50 These inserts are cut by means of knife members 30, 30' and 30''. The knives 30 and 30' are directly adjacent the knives 19 and 24. The knife members 30 and 30' and their associated parts are of identical construction.

This construction and assembly are shown in Fig. 6, which shows the knife 30' connected by a screw 33 to a block 32 which has the same triangular shape as said knife 30'. Said screw 33 also connects the blocks 32 to the adjacent block B.

The piercing points 31a which are associated with the knife 30', are held in a supplemental block 31 which is connected to the block 32 by means of suitable screws or other fastening members. 65

As shown in Fig. 1, a portion of the knife 30'' is close to a portion of the knife 34 so that said closely adjacent portions form a single cutting edge.

As shown in Fig. 1 and in Fig. 7, the knife member 30'' consists of two branches in angular relation, the third edge of said knife member 30'' comprising a portion of the knife 34. The knife 34 is connected to a block 35 which is connected to the 75

base 2, by means of screws or other fastening members 36. The shanks of said screws 36 pass through longitudinal slots 37 of said block 35 so that the block 35 can be longitudinally adjusted. 5 Piercing points 34a are held in three separate blocks or holders 38, 39, 40.

The blocks 38 and 39 are of angular cross-section as shown in Fig. 7 and they are connected to the member 35 by screws or other suitable fastening devices. The block 40 is connected to the block 35, by means of fastening screws 41.

The piercing points are held in said blocks 38, 39 and 40, in the manner previously described.

Piercing points 42 are also associated with the 15 knife member 30² and said piercing points 42 are held in the block 43, which is connected by means of a screw 44 to a block 45. Said block 45 is held to the block 35 by means of a screw 46 whose head is countersunk in the corresponding surface of the 20 block 35.

In the particular embodiment described, decorative stitching is provided along the lines 52. The perforations for said lines of decorative stitching are formed by piercing points 47 which 25 are held in a block 48. Said block 48 is connected by suitable screws to a block 49, which is held to the base 2 by means of bolts 60.

The bolts 60 have their shanks passing through longitudinal slots 61 of the blocks 49, in order to 30 permit longitudinal adjustment of the block 49.

In order to use the device illustrated in Fig. 1, a sheet of leather or other suitable material is placed upon the edges of the cutting knives and over the piercing members, and suitable pressure 35 is applied to the sheet of leather by means of members made of wood or other material which can be easily pierced or cut.

For example the leather blank may be laid upon a wooden table and the device shown in Fig. 1 can 40 be inverted and pressed against said leather blank so as to cut and perforate said leather blank.

The triangular pieces which are formed by the 45 knife members 30 and 30' and 30² preferably remain integral with the main body of the blank, as illustrated in Fig. 16.

The thumb piece 53 of the glove is formed by the die member 62, having a knife 63 connected thereto by means of screws 62a. The piercing members 63a are held in a block 64, which is suitably connected to the member 62 by means of screws 65.

In the particular embodiment shown, the finger portions of the glove are provided with the usual inserts 54. Said inserts 54 are cut by 55 means of a die member 70, having the knife 66 connected thereto by means of screws 67. A slitting knife 66a is detachably mounted in member 70, and it is clamped between blocks 69 and 69', which are connected by screws 65 to member 60 70. Piercing members 68' are mounted in blocks 69 and 69'.

Generally speaking, the dies for cutting out the sections of the glove can be of the usual type so that a further detailed description thereof is 65 not necessary as the invention changes the usual method of manufacturing the glove, only in forming the thread holes in proper spacing and in proper relation to the cut edges of the blank. Therefore reference can be made to well known 70 practice for any further details of the dies and of their knives, and of the gloves.

The glove member which is formed by the die

illustrated in Fig. 13 is the member 54 which is shown in Fig. 18.

Figs. 19-21 conventionally illustrate the assembly of various parts of the glove. These figures also show the sewing thread T which is 5 passed through the sewing perforations S which have been formed by the piercing points.

Therefore the operator has a sure and reliable guide for assembling the portions of the glove blank in proper relation, thus providing sewing 10 which is absolutely uniform and of high quality.

According to the invention, the thread-receiving perforations are formed while cutting the blank. However, the invention is not limited to a method whereby the cutting means and the 15 perforating means operate simultaneously. It is preferred to have the piercing members penetrate the material before or while the cutting means operate, but this is not absolutely necessary, and the invention is not to be so restricted. 20 The preferred device shows the cutting means and the perforating means rigidly connected to the base of the device, and immovable relative to said device, while the device is being used. However, it would not be departing from the in- 25 vention if the perforating means or the cutting means, or both, were mounted movably relative to the base, so as to move perpendicular to the base. In such case, it is preferred to have the knives and piercing members operate in fixed lat- 30 eral relation, so that the perforations are formed accurately relative to the edges or slits which are formed by the knives.

All the parts of the device are detachable from each other and from the base or its flanges. The 35 piercing members and their supports are generally of the same construction, so that the butt ends of the piercing members abut rigid surfaces of the die-means, and defective piercing members can be readily replaced.

Numerous changes and omissions can be made in the details herein, without departing from the 40 spirit of the invention.

We claim:

1. A device for cutting a glove blank and for 45 perforating thread-receiving openings in said blank, said device having cutting means for cutting the blank, said device also having perforated supporting means, perforating members removably located in the perforations of said supporting means, said perforating members having 50 pointed portions which project outwardly of said supporting means, each said supporting means being connected to a base member, the inner ends of said perforating members abutting a 55 surface of said base member.

2. A device for cutting a glove blank and for 60 perforating thread-receiving openings in said glove blank, said device having cutting means for cutting the blank, said device also having perforated supporting means connected thereto, 65 perforating members removably held in operative position in the perforations of said supporting means, said perforating members having pointed ends which project outwardly of said supporting means, and additional means removably connected to said supporting means and holding the perforating members against inward movement relative to said supporting means.
